CLAIM

The ornamental design for a protective case, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top, right, front perspective view of a protective case showing a first embodiment of the new design;

FIG. 2 is a right, rear, top perspective view of the invention illustrated in FIG. 1;

FIG. 3 is a left side view of the invention illustrated in FIG. 1;

FIG. 4 is a rear view of the invention illustrated in FIG. 1;

FIG. 5 is a right side view of the invention illustrated in FIG. 1;

FIG. 6 is a left side view of the invention illustrated in FIG. 1;

FIG. 7 is a top view of the invention illustrated in FIG. 1;

FIG. 8 is a bottom view of the invention illustrated in FIG. 1;

FIG. 9 is a top, right, front perspective view of a protective case showing a second embodiment of the new design;

FIG. 10 is a right, rear, top perspective view of the invention illustrated in FIG. 9;

FIG. 11 is a front view of the invention illustrated in FIG. 9;

FIG. 12 is a rear view of the invention illustrated in FIG. 9;

FIG. 13 is a right side view of the invention illustrated in FIG. 9;

FIG. 14 is a left side view of the invention illustrated in FIG. 9;

FIG. 15 is a top view of the invention illustrated in FIG. 9;

(Continued)

FIG. 16 is a bottom view of the invention illustrated in FIG. 9;
 FIG. 17 is a top, right, front perspective view of a protective case showing a third embodiment of the new design;
 FIG. 18 is a right, rear, top perspective view of the invention illustrated in FIG. 17;
 FIG. 19 is a front view of the invention illustrated in FIG. 17;
 FIG. 20 is a rear view of the invention illustrated in FIG. 17;
 FIG. 21 is a right side view of the invention illustrated in FIG. 17;
 FIG. 22 is a left side view of the invention illustrated in FIG. 17;
 FIG. 23 is a top view of the invention illustrated in FIG. 17;
 and,
 FIG. 24 is a bottom view of the invention illustrated in FIG. 17.
 The broken lines in the drawings represent portions of the protective case that form no part of the claimed design.
